UNITED STATES PATENT OFFICE

ALANSON O. TAYLOR, OF LINCOLN, NEBRASKA

ORE SEPARATOR

Application filed December 18, 1929. Serial No. 414,973.

This invention relates to a separator for ore after the same has been crushed, the general object of the invention being to provide means for subjecting the ore, as it moves downwardly through a chute, to an upwardly moving stream of air which is divided into two parts by a board provided with swinging riffles so that the ore is subjected to two concentrations, one stream of air removing the lighter particles before the ore reaches the board and the other stream removing lighter particles after the ore passes through the board.

A further object of the invention is to provide feeding means for feeding the ore from a hopper into the chute which leads to the air chute, so as to prevent the ore from clogging and to feed it in an even stream to the air chute and to place said chute at an incline which can be changed according to the material to be handled.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

Figure 1 is a vertical sectional view through the device.

Figure 2 is a section on line 2—2 of Figure 1.

In these views, the numeral 1 indicates the casing of the device and 2 indicates the ore hopper which is placed in the upper part of the casing. The diagonally arranged air chute is shown at 3 and the discharge 4 of a fan casing 5 is connected with the lower end of the chute 3. A discharge spout 6 is connected with the upper end of the chute and extends downwardly to a dump or other point of discharge. A delivery chute 7 is connected with the bottom part of the lower end of the chute 3 and passes through the bottom of the casing and discharges into an ore re-

ceiver 8. A discharge chute 9 connects the bottom of the hopper with the upper part of the chute 3 at a point substantially midway the ends of said chute 3.

The fan is shown at 10 and is driven from any suitable means, such as a motor 11, and the fan shaft is belted to a shaft 12 on which is placed a grooved roller 13 placed in the bottom of the hopper and acting to feed the crushed ore therein to the chute 9.

A riffle board 14 is placed in the chute 3 and extends longitudinally thereof, this board being adjustable toward and away from the bottom of the chute 3 through means of the bolts and wing nuts 15 carried by the side pieces of the board and passing through the slots 16 in the sides of the chute 3. Riffle plates 17 are pivoted at their upper edges to the board, as shown at 18, downward movement of the riffle plates being limited by the stops 19, and the lower ends of the riffle plates are curved upwardly, as shown at 20.

From the foregoing it will be seen that the air produced by the fan is delivered to the chute 3 and moves upwardly through the chute, a screen 21 being arranged in the part 4 which acts to evenly distribute the air to the chute. This air is divided into upper and lower currents by the riffle board, so that two concentrations of the ore takes place, one by the upper current acting on the ore and removing therefrom lighter particles before the ore reaches the swinging riffles.

The upper current of air distributes the ore over the riffle board and the second or lower current, passing under the riffles, also acts to remove lighter particles from the ore. The swinging riffle plates act as dampers for holding the current of air close to the top of the ore on the bottom of the chute 3. The heavy particles of ore slide down the chute 3 into the discharge 7, which is provided with a gravity gate 22 which opens under the weight of the air and permits the ore to drop into the receptacle 8.

The swinging riffle plates also act to retard the movement of the ore so that it can be effectively acted on by the lower current. The screen 21 can be replaced by another

one of finer or coarser mesh so as to equalize the air current according to the kind of material being acted on.

5 The arrangement of the parts of this invention is such that no dust escapes except at the discharge 6, and this can be extended any distance from the apparatus.

10 It is thought from the foregoing description that the advantages and novel features of the invention will be readily apparent.

15 It is to be understood that changes may be made in the construction and in the combination and arrangement of the several parts, provided that such changes fall within the scope of the appended claims.

15 What I claim is:—

20 1. An ore separator comprising a casing, a hopper in the casing, a diagonally arranged chute into which the hopper discharges, means for causing air to pass upwardly through the chute, a riffle board longitudinally arranged in the chute and dividing the air current into upper and lower parts, a discharge chute connected with the upper 25 end of the air chute, a discharge chute connected with the bottom part of the lower portion thereof and means whereby the riffle board can be adjusted toward and away from the bottom part of the chute.

30 2. An ore separator comprising a casing, a hopper in the casing, a diagonally arranged chute into which the hopper discharges, means for causing air to pass upwardly through the chute, a riffle board longitudinally arranged in the chute and dividing the air current into upper and lower parts, a discharge chute connected with the upper end of the air chute, a discharge chute connected with the bottom part of the lower portion 35 thereof, and riffle board including pivoted riffle plates having upwardly curved lower edges.

35 3. An ore separator comprising a casing, a diagonally arranged air chute therein, a fan having its discharge connected with the lower end of the chute, a discharge pipe connected with the upper end of the chute, a screen in the discharge of the fan, a hopper in the casing discharging into the air chute 40 at substantially the center thereof, an adjustable riffle board longitudinally arranged in the air chute, riffle plates having their upper edges pivotally connected with the board and their lower edges curving upwardly, said riffle board dividing the air current into upper and lower parts, a discharge chute connected with the bottom portion of the lower end of the chute and a gravity gate in said discharge chute.

45 60 In testimony whereof I affix my signature.
ALANSON O. TAYLOR.
